UNITED STATES PATENT OFFICE

2,261,139

CIRCUIT BREAKER

James H. Burnside, 2nd, New York, N. Y., assignor
to Circuit Breakers Corporation, New York,
N. Y., a corporation of New York

Application June 11, 1940, Serial No. 339,840

16 Claims. (Cl. 200—116)

This invention relates to improvements in circuit interrupting devices of the type including overload actuating mechanism of one form or another for causing the switch to open the circuit when a predetermined load is exceeded.

More particularly, the invention is concerned with circuit breakers which are small, simple structurally, and inexpensive to manufacture so as to be competitive with ordinary fuses as employed in house lighting circuits and the like.

The general, most important, object of the invention is, therefore, to provide in a compact, rugged and inexpensive form a circuit breaker which may be employed in the place of ordinary fuses in house lighting circuits.

A further object of the invention is the provision of a switch of this type so constructed and arranged so as to be manually closable and yet not capable of being held closed when overload conditions exist in the circuit to which it is connected.

A further object of the invention is the provision of a small circuit breaker of this type which will meet the requirements to which devices of this type are subjected before being approved for use, including the breaking of overloaded circuits without sufficient flaming to cause fires or injury.

A more specific object of this invention is to provide circuit breakers of this type of both single and double pole forms mounted in special casings therefor or in a casing similarly shaped and little larger than the usual screw plug type of fuse.

A still further object of the invention is the provision of a circuit breaker in which the cooperating fixed and movable contacts interengage to lock the switch in closed position.

Another object is to provide in a switch of the above type mechanism for automatically destroying the locking engagement between the contacts upon overload.

A still further object of the invention is the provision in circuit breakers of the above type of a structure by means of which the movable member on which the movable contact is mounted is capable of movement under the stresses placed thereupon by reason of the locking interengagement of the contacts to ensure proper alignment of the contacts and hence a low contact resistance therebetween.

A more specific object of the invention is the provision in a circuit breaker of this type of a construction which minimizes wear on the parts most subject thereto in order to ensure the ability

to operate many hundreds of times without wearing out.

A still more specific object of the invention is the provision of a circuit breaker of this type having a bimetal overload release in which the bimetal element is so constructed as to cause a minimum current loss in the device itself when in continuous use.

Another specific object of the invention is the provision of a construction which minimizes the tendency of the adjacent portions of the housing to carbonize and become a high resistance conductor.

Many other and more detailed objects of the invention will be apparent from the following detailed description when taken in connection with the attached drawings.

This invention resides substantially in the combination, construction, arrangement and relative location of parts, all in accordance with this disclosure.

In the accompanying drawings,

Figures 1 to 19, illustrate the single pole form of device with special housing, wherein

Figure 1 is a top plan view thereof;

Figure 2 is a right hand side elevational view thereof;

Figure 3 is a view taken on the line 3—3 of Figure 2, that is, with the cover of the housing removed;

Figure 4 is a bottom plan view of the switch housing as it appears when removed from its supporting base;

Figure 5 is a bottom plan view of the cover for the housing;

Figure 6 is a cross-sectional view taken on the line 6—6 of Figure 1, omitting some details in order to illustrate the explosion chamber;

Figure 7 is a similar view taken on the line 7—7 of Figure 1 showing a portion of the movable contact carrier in elevation;

Figure 8 is a cross-sectional view taken on the line 8—8 of Figure 1;

Figure 9 is a cross-sectional view taken on the line 9—9 of Figure 1;

Figure 10 is an enlarged top plan view of the switch with some parts broken away, the main cover removed, and the movable contact cover removed, showing the switch in open circuit position;

Figure 11 is a similar view showing the carrier moved to its extreme clockwise position;

Figure 12 is a view taken on the line 12—12 of Figure 8 showing certain parts in cross-section and leaving the parts mounted on the lower

side of the main cover in place; these parts being in open circuit position;

Figure 13 is a view similar to Figure 12 but showing the parts in a position corresponding to that of Figure 11;

Figures 14 and 15 are views similar to Figures 10 and 11; Figure 14 showing the parts in position just before the main contacts close and Figure 15 showing the final position of the parts when the contacts are closed;

Figures 16 and 17 are views similar to Figures 12 and 13 with the cover parts in positions corresponding to the position of the other parts as illustrated in Figures 14 and 15, respectively;

Figure 18 is a view taken along the line 15 18-18 of Figure 9;

Figure 19 is an enlarged detailed view of the bimetal element and its support;

Figure 20 is a perspective view of the double-pole form of switch;

Figure 21 is a front elevational view thereof with the top cover removed, that is, on the line 21-21 of Figure 20, showing the operating shaft in cross-section;

Figure 22 is a plan view similar to Figure 21 with the cover of the oscillatable contact carrier removed, showing the switch in "off" position or open circuit position;

Figure 23 is a bottom plan view of the housing with one part broken away;

Figure 24 is a considerably enlarged view similar to Figure 22 with some parts broken away, showing the switch in "on" or closed position;

Figure 25 is a top plan view looking into the main housing with the oscillatable contact carrier removed, showing some parts in cross-section;

Figure 26 is a cross-sectional view taken on the line 26-26 of Figure 22;

Figure 27 is a top plan view of another form of single-pole switch with a circular housing shown in full size;

Figure 28 is a side elevational view thereof;

Figure 29 is a bottom plan view thereof;

Figure 30 is a top plan view with the housing cover removed; and

Figure 31 is a cross-sectional view taken on the line 31-31 of Figure 30.

Reference is made to the fact that the various structures herein disclosed are in some respects similar to the subject matter disclosed in my pending application Serial No. 185,145, filed January 15, 1938, for Circuit breaker, and my issued Patents Nos. 2,162,935 and 2,204,528.

A great deal of effort, time and money has been spent in an attempt to build a circuit breaker which would be comparable in size to the ordinary screw type of fuse plug now commonly employed for the protection of electric light and power circuits. The tests to which such devices are put by the Fire Underwriters Laboratories before they are approved for use are so severe that while circuit breakers have been developed and are sold for this purpose they are relatively large and expensive, with the result that a truly competitive switch for these uses has not yet been produced. The switch herein disclosed is little larger than a screw type of fuse plug, and in accordance with this invention has been so simplified in structure as to be competitive therewith in cost. The devices of the figures of these drawings are substantially full size and it will be seen that the screw plug type of circuit breaker illustrated in the drawings is about the size of a screw plug fuse. The 75

mechanism of the various forms of the invention has been so simplified and constructed as to be capable of meeting all the tests for approval and is entirely capable of withstanding many hundreds of repeated operations.

The details of construction and the purposes thereof will best be understood by describing the various devices as a result of which the objects of the invention will become more apparent. The structure of Figures 1 to 19, inclusive, will first be described.

As illustrated in the various figures, it includes a base 1 of suitable insulating material which, as is clear from the drawings, consists of a substantially rectangular body of insulating material cut away intermediate its ends and throughout its width as indicated at 2 to receive the main housing 3 which is likewise of a substantially rectangular form and is provided with a removable cover 4 held on the housing by means of the screws 5. The housing is held in the base by means of the screws 6. At diametrically opposite corners the base is provided with holes 7 through which screws or bolts may be passed for mounting the switch. At one end of the base is a terminal strip 8 provided with a binding screw 9 by means of which one of the circuit wires may be attached and at the other end is a terminal strip 10 provided with a binding screw 11 by means of which the other circuit wire may be attached. It may be here noted that the structure now being described is of the single pole type.

The removable cover 4 is provided with a short shaft 12, one end of which is secured in any suitable way as by molding in a manual operating knob 13, as illustrated for example in Figure 8. The other end of the shaft, which has flattened sides, as illustrated clearly in Figure 8, has mounted thereon a cam 35 which has a complementary opening so that the shaft and cam must move together. The cam is held on the shaft by means of a screw 34 having a cylindrical head as shown in Figure 8. Thus when the manual operating knob 13 is rotated cam 35 rotates with it close to the under-surface of the cover 4. Formed on top of the cover 4 at a suitable point is a stop 14 which engages one end of the knob 13. In the other end of the knob is a spring pressed detent comprising a ball 15 and a spring 16, see Figure 2. As shown in Figure 1 the cover is provided with a depression 17 in which the ball 15 rests when the switch is in "on" position, at which time it is straight up and down.

The conductor strip 10 extends up into the housing from the bottom, see Figure 8, and has secured thereto in conducting relation the main fixed contact 18. That portion of the housing adjacent this contact is shielded by means of a piece of insulating material 19 of suitable characteristics, such as horn fibre, which does not carbonize in the spark resulting when the circuit breaks. Thus the high resistance of the switch is maintained through a long life.

As is clear from Figure 18, the housing 3 is shaped to form a chamber on the interior thereof of which for a considerable portion thereof is substantially circular. Mounted in this chamber is the movable contact carrier or member 20 which is made of any suitable insulating material, preferably in the form of a cylinder. This member is hollow and contains the operating mechanism of the switch. It is provided with a

removable cover 21 which is held thereon by means of a screw 22. The sides of the carrier 20 and the cover 21 are of complementary shape and interengage so that there is no tendency of one to rotate with respect to the other. On top of the cover 21 is pivotally mounted on the pivot pin 23 a latch 24 which is engaged by a spring 26, as illustrated clearly in Figure 3. The lower end of the latch 24 engages, as will be described later, in a notch 25 in the circular wall of the main housing. A finger 27 extends up through the cover 20 through a suitable opening therein and by means of it, as will be explained later, the switch may be manually opened through the operating knob 13 when desired. The cover 21 has an upwardly extending shoulder 28 formed thereon for cooperation with the cam 35, as will be explained later.

Extending downwardly through the wall of the main housing in the region of the fixed contact 18 is a passage 29, see Figure 6, which opens into a chamber 30 formed by a recess in the bottom of the housing 4, which is closed by the base 1 when the parts are assembled. The base 1 is provided with an aperture 30' which connects this chamber with the atmosphere.

In the bottom wall of the main casing 3 is a recess in which a spiral spring 31 lies. The inner end of this spring engages in a slot in the lower end of a lead strip 43 (Figure 4) which extends upwardly into the carrier 20, as clearly illustrated in Figure 8. The outer end 31' of the spring rests in a radial slot in the housing 3. Also secured in the end of the conductor strip 43 by means of solder or other suitable fastening means is one end 32 (Figure 4) of a flexible pigtail or stranded conductor 33. The other end of this conductor is secured, as by soldering, to the terminal strip 8.

As illustrated in Figure 5, the cam 35 is provided with a working face 36, a shoulder 40, and another working face 35' for purposes to be later described. Mounted on the lower face of the cover 4 on a pivot pin 37 is a latch 39 which is held in the position shown in Figure 5 by means of a spring 38 and a stop 38' secured on the cover.

The cylindrical carrier 20 is provided with a central hub 41 which projects into a hole in the base of the housing 3 in alignment with the coil spring 31. At the point of the connection between the hub 41 and the carrier 20 is an integral shoulder or collar 42 which rests on the top side of the bottom wall of the casing. It will be noted that the hub 41 has a loose fit in the passage in which it lies. At this point it will be noted that the head of screw 34, see Figure 8, projects into a central hole in the cover 21 of the movable member 20. This hole is large enough to likewise provide a loose fit for a purpose to be described later.

Referring to Figure 18, it will be seen that the bottom wall of the casing 3 in the main chamber is cut away to form a groove which is partly circular and partly straight, as indicated at 44, which straight side gradually recedes from the center of the chamber. At 20' is a lug formed on the bottom of the carrier 20, see also Figure 9, which serves as a stop by engaging the end wall of the circular portion of the groove to limit the counter-clockwise or circuit opening movement of the carrier 20. A finger 45 projects into this groove for cooperation with the cam surface 44. This finger piece is an integral part of a lever 47, see Figures 10 and 14, for example, and

projects down through the bottom wall of the carrier, as is clear from Figure 9.

Referring to Figures 10 and 14, for example, it will be seen that the lever 47 is pivotally mounted on a pivot pin 46 secured on the bottom wall in the carrier 20. This lever is of bellcrank formation and is pivotally connected by the arm 48 thereof at 49 to a pair of links 50. Pivotally mounted between these links at 52 is a contact 51 which is positioned for sliding movement in the direction of its length along a chord of the cylindrical carrier, as is clear from Figure 10. This contact may slide through an opening 20" in the side wall of the carrier 20. A pivot pin 53 is secured on the other arm of the bellcrank lever 48 and mounted on it is a very small lever having a pair of projecting ears 54 and 55 which are connected by faces which meet at an acute angle, as is clear in Figure 11. Extending in an opposite direction from the pivot pin 53 is an ear 56 positioned to engage an integral upstanding stop 57 on the adjacent portion of the bellcrank lever 47. A spring 58 engages the little lever on the pivot pin 53 to hold it against the stop, as shown in Figure 11. The bellcrank lever 47, the little lever pivoted on it, and the links 50 are preferably made of metal but need not necessarily be made of metal since they do not carry any current. A larger spring 52' is mounted on the pivot pin 46 and engages the linkage at the pivot point 49 and the inner wall of the carrier 20. As will be seen from Figures 10 and 11, the lever 47, the links 50 and the contact 51 form a toggle arrangement and the spring 52' tends to move this toggle arrangement out of straight line position to the broken down position shown in Figure 10.

At this point it may be noted that the finger piece 27 is on a lever 27a pivotally mounted on the under-side of the cover 21 of the carrier. Also mounted on this lever so as to depend down into the carrier is a finger piece 27' which occupies various positions as indicated in the drawings.

At 59 is a right angle support which is secured in the carrier to the lead strip 43 by means of a screw 43'. Secured to the support 59 is a bimetal arm 60 which is connected to the contact 51 by means of a flexible lead or pigtail 62. The lead is secured to the contact in any suitable way, as by soldering or the like, and is attached to the bimetal arm 60 by means of a clip 61, solder, rivets, and the like. As illustrated in Figure 19, the bimetal lever 60 is connected to the lead intermediate its ends. The free projecting end 60' is of less width, and hence mass, than the remainder thereof for a purpose to be described later.

The manner in which this device operates will now be described, it being first noted that the switch has three positions, "off," "re-set," and "on," as indicated on the cover, see Figure 1. It will be of some help to realize that the parts are shown in Figures 1, 3, 5, 10 and 12 in "off" position; in Figures 14 and 16 in "re-set" position; and in Figures 15 and 17 in "on" position. There is a position between the "off" and "re-set" positions which is indicated in Figures 11 and 13. When the parts are in "off" position the operating handle or knob 13 is in the position shown in Figure 1, which leaves the cam 35 and the latch 39 in the position shown in Figure 5. The carrier 20 is in the position shown in Figures 3 and 10, the latter of which shows the position of the parts within the cover. Figure 12 shows the

position of the parts on the cover as well as the position of the carrier.

In order to close the device the operator turns the knob 13 in a clockwise direction from the "off" position, as far as it will go, bringing its upper end in the region of the "re-set" position. In doing this he causes the carrier 20 to rotate from its position in Figure 10 to its position in Figure 13. The carrier is caused to move to this position by reason of the fact that the face 36 of the cam 35 has engaged the shoulder 28 on the cover 21 of the carrier 20. During movement to this position the finger 45 has moved out along the cam face 44, Figure 18, and in so doing has caused the bellcrank lever and connected linkages to move out to a straight line position as shown in Figure 11, projecting the contact 51 from its withdrawn position, Figure 10, to the position shown in Figure 11. The little lever on the pivot pin 53 has moved to the position shown in Figure 11 under the influence of spring 58. To do this the rear end of the ear 54 rubbed against the left hand face of the bimetal element 60, Figure 11, causing the little lever to pivot on the pivot pin 53 against the action of spring 58. Thus this part of the device is free of this structure so that the latch ear 54 may move past the relatively rigid bimetal element 60 by swivelling on its pivot pin 53 without practically any wear. The only force to be overcome is that of the light spring 58. Likewise during this motion the spring 31 in the bottom of the device is placed under stress so that as soon as the pressure is let up on the knob 13 or it is turned backwardly, that is, in a counter-clockwise direction, the carrier 20 will move back a short distance until the latch lever 24 engages in the notch 25 in the circular wall of the housing 3, see Figure 16. If the knob is released the parts stop in this position. At this time, as is clear from Figure 16, it will be seen that although the contact 51 is projected it does not engage the fixed contact 18. Thus the main circuit is not yet closed. This is the in-between position referred to before.

In order to put the device in "on" position, the knob 13 is rotated to "on" position and as this is done the face 35' of the cam 35 moves around to engage the adjacent end of the latch 24 and moves it out of the notch 25. This frees the carrier so that under the influence of spring 31 it moves to the position shown in Figures 15 and 17, at which time contacts 51 and 18 engage to lock the carrier against any further movement. This movement of cam 35 causes the shoulder 40 on it to pass the latch 39 so that any attempt to again rotate the knob in a clockwise direction will be prevented. This involves the so-called "free tripping" of the device, that is to say, that once it moves to closed circuit position it is out of the control of the operator to the extent that he could not hold it in that position. Thus, if the circuit is closed on an overload it cannot be held on it and is free to immediately open the circuit. The latch 39 cooperates with the side of the carrier 20, which is a little higher than the plane of the top of the carrier, as is clear from Figure 8 and which portion includes the shoulder 28. Thus when the switch goes to "off" position the latch 39 is moved out of the way so that the cam 35 may pass it during motion of the device to "re-set" position.

In the "on" position, the parts as stated above are as illustrated in Figures 15 and 17. The toggle linkage which includes the contact 51 is in a

straight line and is held against being collapsed by the spring 52' because the ear 54 of the little lever is bearing against the bimetal element 60 and the ear 56 engages the stop 57 so that this condition cannot be disturbed. With the device in "on" position, current flows from the circuit through contact 18, contact 51, flexible connection 82, that portion of the bimetal element 60 between the clip 61 and the support 59 through the support to the center lead 43 through the flexible connection 31 on the bottom of the device to the other circuit wire.

When an overload develops in the device the bimetal element 60 is so constructed that it curves outwardly, that is, its free end moves toward the right, Figure 15, until it disengages the ear 54. When this happens spring 52' will force the toggle linkage out of alignment so that it collapses, withdrawing the contact 51 into the carrier. The result is that the locking engagement of that contact with the fixed contact 18 is destroyed and the relatively heavy coil spring 31 causes the carrier to snap to the "off" position, Figure 10. At this point it may be noted that the acute angle formed between the ears 54 and 55 on the little lever is provided so that the device may be accurately calibrated in order that the end of the bimetal element will engage the ear 54 always at the same place and not at the corner of the angle where dirt, burrs, and other material might collect to interfere with the accuracy of operation.

At this point it might be well to also note that the bimetal element is made as illustrated in Figure 19 so that only a portion of it is included in the circuit, thereby reducing the resistance of this portion of the circuit and keeping the load imposed by the device, which is a "loss load," small. The end 60' of the bimetal element is of reduced section so that it will heat by conduction to the same temperature as the rest of the element so that the whole element will perform its function.

Another advantage of this arrangement is that it removes the connection from the region of the point of engagement between the bimetal element and the latching ear 54, thereby simplifying the structure. Likewise, it may be noted that the carrier is relatively free in its supports at the hub 41 and the screw 34 so that it can be moved around under the stresses on the device at closed circuit position so that the contacts 51 and 18 may properly align to ensure locking and a maximum area of contact therebetween. The construction provides what may be termed a floating contact carrier or member because of its freedom of motion to permit proper alignment of the contacts. Since the end faces of contacts 51 and 18 are plane and it is across these faces that the current flows, it is naturally desirable that the maximum area of contact result. The spring 31 exerts a fairly large force on the device and by leaving the carrier free in the manner explained the contacts can properly engage. The collar or shoulder 42, Figure 8, ensures that there will not be any undue tipping of the carrier while allowing this alignment of the parts.

When the device springs to open circuit condition any arc that may be drawn between the contacts 51 and 18 is drawn, Figure 17, in a counter-clockwise direction down into the narrow confines of the arcuate chamber between the wall of the housing and the wall of the carrier. At the same time the gases generated rapidly build up the pressure in this restricted chamber so that the

arc is rapidly extinguished. This pressure is relieved through passage 29 into chamber 30, see Figure 6, and finally escapes through the port 30'. By the time it reaches the atmosphere it has sufficiently expanded and cooled so that it is no longer a source of fire or injury hazard.

When the device is in "on" position as shown in Figure 17 it may be manually put in "off" position by turning the knob 13 from its up and down position to its "off" position. As this movement occurs, the face 35', Figure 12, of cam 35 engages the finger 27, causing it to rotate in a counter-clockwise direction. This moves the finger 27', Figure 17, into engagement with the free end 60' of the bimetal element and then springs it out of engagement with the ear 54. This, of course, frees the toggle so that the spring 52' may collapse it and the device springs to "off" position. The carrier is stopped in its opening movement at about the time spring 31 has expended its force by engagement of the lug 20' on the bottom of the carrier 20 with the end of the arcuate groove in the bottom of the casing 3, see Figure 18. The device is then ready for a new cycle of operations to close the circuit to which it is connected.

For emphasis it may be noted that the plane of engagement between the faces of the contacts 51 and 18 is offset or at an angle to a tangent to the carrier in the region of the contact so that there is a sort of wedging action resulting from the attempt of the contact 51 to move past the contact 18 as long as contact 51 is held in projected position. This ensures a positive lock and thereby eliminates separate locking mechanism for holding the carrier in circuit closed position. The contact 51 moves through an opening in the side wall of the carrier 20 so as to engage the sides of the opening at its sides and thereby allow it only a straight line or longitudinal movement. In other words, the slot 20', see Figure 10, in which an ear of the cover 21 lies, connects with a lower slot 20a in which the contact 51 has a sliding fit.

The double-pole switch of Figures 20-26, inclusive, will now be described in detail. In starting, it may be noted that Figures 21, 22, 23 and 25 are full size. As before, the device is shown with an insulating base 70, shaped similar to that of the single-pole switch. Mounted on this base is a rectangular housing 71 having a removable cover 72 and an operating knob 73 as before. In this case the base is provided with four terminal strips 74, 75, 76 and 77 in view of the fact that it is a double-pole structure. These terminal strips are provided with binding screws for attachment of the circuit wires in accordance with the usual practice. As is clear from Figure 23, the terminal strip 77 extends up into the housing and has mounted thereon the fixed contact 78 which projects through an opening in the horn fibre strip 79 which protects the housing against carbonizing. In a similar way the terminal strip 74 extends up into the housing and is provided with the other fixed contact 80 extending through the horn fibre protecting strip 81. Mounted on the central top surface of the housing, which is slightly depressed below the rim which receives the cover, is a removable piece of suitable material, such as hard fibre 82, held in place by a screw 83 and providing a shoulder 84 for a purpose to be described later.

At 85 is a cylindrical movable contact carrier which is provided, as in the case of the single-pole switch, with a removable cover 85'. At 86 is an angled lever pivotally mounted on a pivot 75

pin 87 secured to the cover 85' and arranged so that when the switch is in "re-set" position the heel of that lever will engage the shoulder 84 and hold the member 85 in that position until released for movement to "on" position as before.

A spring 88 bears on the lever 86 to urge it to a position to engage the shoulder 84 as the rotor moves from the position shown in Figure 1 in a clockwise direction to "re-set" position (that is, the position corresponding to that of the single-pole switch in Figure 11). Pivotaly mounted on the cover 85' on the pivot 89 is a U-shaped lever 90, in the slot of which engages a pin 92 coming up through a slot in the cover 85', as is clear from Figures 21 and 26. A spring 91 engages a shoulder on the cover 85' and a projection 90' on the lever 90 so as to hold it in the position shown in Figure 21. Mounted on the cover 72 is a short shaft 93, to the outer end of which is secured the operating knob 73. The inner end of the short shaft 93 has straight sides, as is clear from Figure 21, on which is locked a cam 94 which is held thereon by means of a round head screw 95. As shown in Figure 26, this screw fits loosely into a central opening 85" in the cover 85' of the oscillatable contact carrier 85.

At this point it may be noted that the U-shaped lever 90 has its longer end curved upwardly, as indicated in Figure 26, to engage a working surface on the cam 94, as will be explained later. The cam 94 is provided with an ear as shown positioned to engage an upstanding shoulder 94' on the cover 85' and by means of which the carrier 85 may be rotated in a clockwise direction by the knob 73 to move it to "re-set" position. As shown in Figure 24, the cavity in the main housing 71, in which the oscillatable carrier 85 moves, has two arcuate walls 71' closely spaced to the carrier to form restricted arcuate chambers into which the arcs are drawn when the switch breaks the circuit. At the end of each of these restricted passages are passages 96 and 98, respectively, going down through the housing and opening into expansion chambers 97 and 99, respectively, as is clear from Figure 23. As in the case of the single-pole switch, the expansion chambers open to the atmosphere through holes in the base 70 positioned at the opposite ends of the chambers from the passages 96 and 98.

As is clear from Figure 26, the carrier 85 is provided with a central depending hub 100 of insulating material, as is the carrier 85 and its cover 85'. It will be seen from this figure that the hub 100 forms a loose fit in the circular passage 101 in the housing through which it passes. The carrier 85 is provided with a reentrant central portion extending in an axial direction with respect to the hub 100, on which is secured, by means of a screw 103, a double-ended lever 102, the shape of which clearly appears in Figure 24. The lower terminal end of the hub 100 is cut away on a diameter to provide two levers, as is clear from Figure 26. Extending down through this hub are the metal strips 104 and 106, which are secured in place by screws, as shown. The lower ends of these strips are respectively connected to the pigtail or flexible connectors 105 and 107 by means of solder, riveting, and the like. The other end of the pigtail 105 is connected to the terminal strip 76, as is clear from Figure 23, and the other end of pigtail 107 is connected to the terminal strip 75. Interposed between these pigtails is the disc 109 of any suitable insulating material. A spiral spring 108 surrounds

the central hub 100 and has one end locked in the hub, as is shown in Figure 25, and the other end in a slot in the adjacent part of the housing 71.

The upper end of the conducting strip 104 is secured in any suitable manner to a bimetal element 110 and likewise secured to the upper end of the conducting strip 106 is another bimetal element 111. As shown in Figure 24, these bimetal elements extend horizontally and parallel to each other. When the switch is in closed position, as shown in Figure 24, the free end of the bimetal element 110 engages an upstanding pin 102' secured on one arm of the double-ended lever 102. Similarly, the free end of bimetal element 111 engages the upstanding pin 92, secured on the other end of the double-ended lever 102. Pivotaly mounted on a pivot pin 112 in the bottom of the cavity of the carrier 85 is a bellcrank lever 113, one arm of which has an upstanding projection 114 which fits in a notch in the adjacent end of the lever 102, see Figure 24. The other arms of the bellcrank lever 113 is pivotally connected at 115 to a pair of links 116, which in turn are pivotally connected to the contact 117 which cooperates with the fixed contact 80. The pair of links 116 engage the contact 117 on both sides in a manner similar to the construction of the single-pole switch. A pigtail or flexible connection 118 is attached to the bimetal element 111 and directly to the contact 117. A spring 119, mounted on the pivot pin 112, engages at one end with the inner wall of the carrier 85 and at the other end with the toggle linkage adjacent the pivot pin 115.

The construction of the other half of the device is similar. Pivotaly mounted on a pivot pin 121 secured in the carrier 85 is a bellcrank lever 122 which has an upstanding projection 123 engaging in a notch in the other end of lever 102 when the switch is closed. The other arm of the bellcrank is pivotally connected at 124 with a pair of links 125 which pivotally connect with the contact 126 which cooperates with the fixed contact 78. A pigtail 129 connects the bimetal element 110 directly with the contact 126. A spring acts on this toggle arrangement in the same manner as does the spring 119 act on its toggle arrangement. Bellcrank 113 is provided with a downwardly extending projection 120 which passes through a slot in the bottom wall of the carrier 85, as is clear from Figure 26. Similarly, the bellcrank 122 has a downwardly extending projection 127.

The bottom wall of the chamber in the housing 71 in which the carrier 85 oscillates is provided, as shown in Figure 25, with grooves shaped to provide camming surfaces 120' and 127' with which the downwardly extending fingers 120 and 127 cooperate so that as the member 85 rotates in a clockwise direction to "re-set" position these fingers engage the camming surfaces and move the bellcrank levers about the pivot pins to straighten out the toggles so as to project the contacts 117 and 126. Projecting downwardly from the carrier 85 are integral projections 85a and 85b which engage the ends of the recesses in the bottom wall of the housing 71, as shown in Figure 25, to limit the oscillation of the carrier 85 in its open circuit movement.

The operation of this switch is quite similar to the operation of the single-pole switch. The knob 73 is rotated from the "off" position, Figure 20, to the "re-set" position as the first operation in closing the switch. This movement of the

knob 73 causes the movable carrier 85 to rotate with it through the co-action between the cam 94 and the shoulder 84', Figure 21, as previously explained. As the carrier reaches "re-set" position, the heel of lever 86 engages shoulder 84 to hold the carrier there. At this time spring 108 is under tension and the contacts 117 and 126 have been projected by reason of the fact that the bellcrank levers have been rotated on their pivot pins through the engagement of the fingers 127 and 120 with the cam surfaces in the bottom of the housing. The carrier now stays in this "re-set" position even if the knob 73 is released. At this time the contacts 117 and 126 do not engage their respective fixed contacts 80 and 78. Thus the circuit is still open.

To close the circuit, the knob 73 is moved back to "on" position (a ball detent, as before, in the knob engaging a depression in the cover 72). As the knob is moved back to "on" position the cam is shaped to engage the adjacent end of lever 86, causing its heel to disengage the shoulder 84. Thus the carrier, under the influence of spring 108 as in the case of the single-pole switch, moves in a counter-clockwise direction so that the projected contacts 117 and 126 engage their respective fixed contacts. The engaging faces are at angles to the circular path of movement of the carrier and, therefore, a wedging action results to lock the carrier 85 in closed circuit position. This position is maintained because the toggle mechanism of which contacts 117 and 126 are a part are extended and cannot collapse because the upstanding projections 114 and 123 engage the double-ended lever 122 as shown in Figure 24.

The circuit is as follows, starting for example from terminal strip 74. The current flows through this strip to contact 80, through contact 117, flexible connection 118, bimetal strip 111, conducting strip 106, pigtail 107, to terminal strip 75. The current continues on through the load back to terminal strip 77, contact 78, contact 126, flexible connection 129, bimetal element 110, conducting strip 104, pigtail 105, to terminal strip 76.

If an over-load develops in the circuit, either one or both of the bimetal elements 110 and 111 will be distorted so that their free ends move outwardly, and through engagement with the pins 92 and 102' cause the double-ended lever 102 to rotate in a clockwise direction, see Figure 24. When this movement has gone far enough to disengage lever 102 with the upstanding projections 114 and 123, the bellcrank levers 113 and 122 are free and their associated springs cause them to collapse, withdrawing the contacts 117 and 126 into the carrier 85. This breaks the locking engagement between those contacts and the associated fixed contacts whereupon spring 108 snaps the carrier in counter-clockwise direction, Figure 24, to instantly open the circuit.

The switch may be moved from "on" position to "off" position manually by rotating the handle 73 to "off" position. This carries with it the cam 94 which engages the bent-up end of the U-shaped lever 90, see Figure 26, to cause it to move the pin 92 extending upwardly from the lever 102 so as to move that lever in the same direction as with the bimetal elements if overheated and thereby release the toggles for collapse. The pin 92 extends to a sufficient height so as to project through the cover 85' of the carrier 85 while the pin 102' is shorter.

For sake of emphasis, it is mentioned sepa-

rately that as indicated in Figure 26 the carrier 85 oscillates on freely fitting supports so that when the switch goes into "on" position the carrier may adjust its position to ensure that the contacts 117 and 126 will have face to face engagement with the contacts 80 and 78, respectively, to give a maximum area of contact and a minimum contact resistance.

In Figures 27 to 31, inclusive, is shown the final form of the structure, which in this case is of the single-pole type. This device is shaped similar to the ordinary safety fuse plug and is little larger than it, being shown in Figures 27 to 30 in full size position. The main housing 130 in this case is cylindrical and is provided with a removable cover 131, above which is the operating knob 133. Projecting from the lower end of the casing 130 is the screw plug 132 by means of which the device may be mounted in the well-known type of fuse block. The central contact 134, as in the case of a fuse, is one terminal of the circuit breaker while the threaded shell 137 is the other terminal. A conducting strip 135 extends from the shell 137 into the housing and on it is mounted the fixed contact 138. In the housing is the oscillatable carrier 136 of a construction just like that of the single-pole switch previously described in full detail. At 139 is the movable contact which projects through this carrier to engage the fixed contact when the switch is closed. The pigtail connects the contact 134 with the interior of the carrier as before and the spiral spring 140 is connected thereto as before. The construction of this switch is otherwise like that of the single-pole type and its operation is exactly the same.

From the above description it will be apparent to those skilled in the art that the invention herein disclosed may be embodied in still other physical structures without departure from the novel subject matter thereof. I do not, therefore, desire to be limited to the disclosure as given for purposes of illustration but rather to the scope of the claims granted me.

What I claim is:

1. In a circuit breaker, a closed housing forming a chamber, a fixed contact mounted in said chamber, an oscillatable carrier in said chamber, a contact on said carrier positionable to engage said fixed contact when the carrier is in closed circuit position, means for urging the carrier to open circuit position, said contacts when in engagement locking the carrier in closed circuit position, and means for loosely confining the carrier to an axis of oscillation whereby the carrier is moved by said means with respect to said axis to cause alignment of said contacts when they are engaged.

2. In a circuit breaker, a closed housing forming a chamber, a fixed contact mounted in said chamber, an oscillatable carrier in said chamber, a contact on said carrier positionable to engage said fixed contact when the carrier is in closed circuit position, means for urging the carrier to open circuit position, said contacts when in engagement locking the carrier in closed circuit position, and means in said housing and on said carrier freely cooperating to provide a relatively fixed axis of oscillation for said carrier whereby the carrier is moved by said means with respect to said axis to cause alignment of said contacts when they are engaged.

3. In a circuit breaker, a closed housing forming a chamber, a fixed contact mounted in said chamber, an oscillatable carrier in said chamber,

ber, a contact on said carrier positionable to engage said fixed contact when the carrier is in closed circuit position, means for urging the carrier to open circuit position, said contacts when in engagement locking the carrier in closed circuit position, means for loosely confining the carrier to an axis of oscillation whereby the carrier is moved by said means with respect to said axis to cause alignment of said contacts when they are engaged, and heat responsive means on said carrier connected in circuit with said contacts when closed to move the contact on the carrier to destroy its locking engagement with the fixed contact upon overload.

4. In a circuit breaker, a closed housing forming a chamber, a fixed contact mounted in said chamber, an oscillatable carrier in said chamber, a contact on said carrier positionable to engage said fixed contact when the carrier is in closed circuit position, means for urging the carrier to open circuit position, said contacts when in engagement locking the carrier in closed circuit position, means in said housing and on said carrier freely cooperating to provide a relatively fixed axis of oscillation for said carrier whereby the carrier is moved by said means with respect to said axis to cause alignment of said contacts when they are engaged, and heat responsive means on said carrier connected in circuit with said contacts when closed to move the contact on the carrier to destroy its locking engagement with the fixed contact upon overload.

5. In a circuit breaker, a closed housing forming a chamber, a fixed contact mounted in said chamber, an oscillatable carrier in said chamber, a contact on said carrier positionable to engage said fixed contact when the carrier is in closed circuit position, means for urging the carrier to open circuit position, manual means for moving said carrier so that the contact thereon has moved past said fixed contact, and means on said carrier for holding it in that position, said manual means on initial reverse movement releasing said holding means whereby the carrier moves back to cause locking engagement between said contacts.

6. In a circuit breaker, a closed housing forming a chamber, a fixed contact mounted in said chamber, an oscillatable carrier in said chamber, a contact on said carrier positionable to engage said fixed contact when the carrier is in closed circuit position, means for urging the carrier to open circuit position, manual means for moving said carrier so that the contact thereon has moved past said fixed contact, means on said carrier for holding it in that position, said manual means on initial reverse movement releasing said holding means whereby the carrier moves back to cause locking engagement between said contacts.

7. In a circuit breaker, a fixed contact, an oscillatable member having a contact thereon, said member being positionable to engage said contacts, means acting on said member always tending to move it to contact disengaging position, a manually operated actuator engageable with said carrier to move it beyond circuit closed position against the resistance of said means, and means for holding the carrier in that position, said manual actuator upon initial reverse movement releasing said holding means whereby the carrier moves in the reverse direction to

cause the contact thereon to engage the fixed contact and hold the carrier in that position.

8. In a circuit breaker, a fixed contact, an oscillatable member having a contact thereon, said member being positionable to engage said contacts, means acting on said member always tending to move it to contact disengaging position, a manually operated actuator engageable with said carrier to move it beyond circuit closed position against the resistance of said means, means for holding the carrier in that position, said manual actuator upon initial reverse movement releasing said holding means whereby said carrier moves in the reverse direction to cause the contact thereon to engage the fixed contact and hold the carrier in that position, and heat responsive means in circuit with said contacts for moving the contact on the carrier with respect to the fixed contact upon an overload whereby said means snaps said carrier back to initial position.

9. In a circuit breaker, a housing forming a chamber, a fixed contact mounted in said chamber, an oscillatable hollow carrier in said chamber, a contact slidably mounted in said carrier, said contact being positioned substantially within said member in the open circuit position of the member, means in said member for causing the contact thereon to project from the member in closed circuit position, means for urging said member to open circuit position, and a manual actuator for moving said member to closed circuit position whereby the contact on the member is projected to engage the fixed contact and hold the member in circuit closed position.

10. In a circuit breaker, a housing forming a chamber, a fixed contact mounted in said chamber, an oscillatable hollow carrier in said chamber, a contact slidably mounted in said carrier, said contact being positioned substantially within said member in the open circuit position of the member, means in said member for causing the contact thereon to project from the member in closed circuit position, means for urging said member to open circuit position, a manual actuator for moving said member to closed circuit position whereby the contact on the member is projected to engage the fixed contact and hold the member in circuit closed position, and heat responsive means in said member for causing withdrawing movement of the contact on the member to release it for open circuit movement.

11. In a circuit breaker of the type described, the combination including a housing having a fixed contact thereon, an oscillatable carrier in said housing having a contact therein, spring means for urging the carrier to open circuit position, and means for moving the carrier to closed circuit position and for projecting the contact therein so as to engage the fixed contact and hold the carrier in closed circuit position.

12. In a circuit breaker of the type described, the combination including a housing having a fixed contact thereon, an oscillatable carrier in said housing having a contact therein, spring means for urging the carrier to open circuit po-

sition, means for moving the carrier to closed circuit position and for projecting the contact therein so as to engage the fixed contact and hold the carrier in closed circuit position, and heat responsive means in circuit with said contacts for moving the contact on the carrier back thereto upon overload to release the carrier for movement to open circuit position.

13. In a double-pole circuit breaker, the combination including a housing having a pair of fixed contacts therein, an oscillatable carrier in said housing, means for urging said carrier to open circuit position, a pair of contacts on said carrier, and means for moving the carrier to closed circuit position and moving the contacts on the carrier to a position to engage the fixed contacts respectively to lock the carrier in closed circuit position.

14. In a double-pole circuit breaker, the combination including a housing having a pair of fixed contacts therein, an oscillatable carrier in said housing, means for urging said carrier to open circuit position, a pair of contacts on said carrier, means for moving the carrier to closed circuit position and moving the contacts on the carrier to a position to engage the fixed contacts respectively to lock the carrier in closed circuit position, and heat responsive means in circuit with each pair of contacts for moving the carrier contacts from locking engagement with the fixed contacts upon an overload.

15. In a double-pole circuit breaker, the combination including a housing having a pair of fixed contacts therein, an oscillatable carrier in said housing, means for urging said carrier to open circuit position, a pair of contacts movably mounted on said carrier, means for moving said carrier to circuit closed position and moving said contacts with respect to the carrier to cause their engagement with the fixed contacts respectively, means on said carrier for holding the contacts thereon in said positions, and heat responsive means in circuit with said contacts to move said last means to release said contacts upon the development of an overload, the cooperation between the contacts in pairs holding the carrier in closed circuit position.

16. In a double-pole circuit breaker, the combination including a housing having a pair of fixed contacts therein, an oscillatable carrier in said housing, means for urging said carrier to open circuit position, a pair of contacts movably mounted on said carrier, means for moving said carrier to circuit closed position and moving said contacts with respect to the carrier to cause their engagement with the fixed contacts respectively, means on said carrier for holding the contacts thereon in said positions, heat responsive means in circuit with said contacts to move said last means to release said contacts upon the development of an overload, the cooperation between the contacts in pairs holding the carrier in closed circuit position, and manual means for moving said holding means to destroy the locking engagement between said contacts when desired.

JAMES H. BURNSIDE, 2ND.
